UNITED STATES PATENT OFFICE

OTTO J. CANEGISER, OF CHICAGO, ILLINOIS.

DESIGN FOR A BOTTLE.

49,722.

Specification for Design. Patented Oct. 3, 1916.

Application filed June 26, 1916. Serial No. 106,067. Term of patent 14 years.

To all whom it may concern:

Be it known that I, OTTO J. CANEGISER, a citizen of the United States, residing at Chicago, in the county of Cook and State of Illinois, have invented a new, original, and ornamental Design for a Bottle, of which the following is a specification, reference being had to the accompanying drawing, forming part thereof.

The figure is a view in perspective of a bottle, showing my new design.

I claim:

The ornamental design for a bottle, as shown.

OTTO J. CANEGISER.

Witnesses:

LEWIS T. GREIST,
MILTON T. MILLER.
